CLAIM

The ornamental design for a handle for grass shears, as shown and described.

DESCRIPTION

FIG. 1 is a left side elevational view of a handle for grass shears showing my new design, the broken line showing of the shear blade mechanism being for illustrative purposes only and forming no part of the claimed design.

FIG. 2 is a top plan view thereof;

FIG. 3 is a bottom plan view thereof;

FIG. 4 is a front elevational view thereof;

FIG. 5 is a right side elevational view thereof;

FIG. 6 is a right side elevational view thereof showing the handle in a retracted position; and

FIG. 7 is a rear elevational view thereof.

FIG. 5

FIG. 6

FIG. 7
